POWER MOWER

Clifford H. Flanigan, New Albany, Ind.

Application October 14, 1948, Serial No. 149,116

Term of patent 14 years

(Cl. D40—1)

To all whom it may concern:

Be it known that Clifford H. Flanigan, a citizen of the United States and a resident of New Albany, in the county of Floyd and State of Indiana, has invented a new, original, and ornamental Design for a Power Mower, of which the following is a specification, reference being had to the accompanying drawing, forming part thereof.

I claim:

The ornamental design for a power mower, as shown.

CLIFFORD H. FLANIGAN.
